UNITED STATES PATENT OFFICE.

JOHN J. LAVER, OF CHICAGO, ILLINOIS.

DESIGN FOR A PACK OF PLAYING-CARDS.

59,757.

Specification for Design.

Patented Nov. 22, 1921.

Application filed June 23, 1921. Serial No. 479,937. Term of patent 14 years.

To all whom it may concern:

Be it known that I, JOHN J. LAVER, a citizen of the United States, residing at Chicago, in the county of Cook and State of Illinois, have invented a new, original, and ornamental Design for a Pack of Playing-Cards, of which the following is a specification, reference being had to the accompanying drawings, forming a part thereof.

The drawings are a face view of each of the cards in a pack showing my new design.

I claim:—

The ornamental design for a pack of playing cards, substantially as shown.

JOHN J. LAVER.
